UNITED STATES PATENT OFFICE.

JULIUS A. FOX, OF NEW YORK, N. Y., ASSIGNOR TO H. MENDES & COMPANY, OF NEW YORK, N. Y., A CORPORATION OF NEW YORK.

DESIGN FOR A TEXTILE FABRIC.

Application filed February 16, 1927. Serial No. 20,782. Term of patent 14 years.

To all whom it may concern:

Be it known that I, JULIUS A. Fox, a citizen of the United States of America, residing at New York city, New York, have invented a new, original, and ornamental Design for a Textile Fabric, of which the following is a specification, reference being had to the accompanying drawing, forming part thereof.

The drawing illustrates a piece of fabric showing my design.

I claim:

The ornamental design for a textile fabric as shown.

Dated at New York city, New York, this 15th day of February, 1927.

JULIUS A. FOX.
